UNITED STATES PATENT OFFICE.

FRANK V. BURMAN, OF BAY CITY, MICHIGAN, ASSIGNEE TO BAY CITY IRON CO., OF BAY CITY, MICHIGAN.

ANGLE-IRON-BENDING MACHINE.

1,144,459.

Specification of Letters Patent. Patented June 29, 1915.

Application filed February 9, 1914. Serial No. 817,545.

To all whom it may concern:

Be it known that I, FRANK V. BURMAN, a subject of the Emperor of Russia, residing at Bay City, in the county of Bay and State of Michigan, have invented certain new and useful Improvements in Angle-Iron-Bending Machines; and I do hereby declare the following to be a full, clear, and exact description of the invention, such as will enable others skilled in the art to which it appertains to make and use the same. This invention relates to angle-iron bending machines.

The object of my invention is to provide a machine so constructed that angle-irons, T-irons and the like may be bent to any desired curvature, with the flange or rib either in or out; and further to bend the angle-iron in such a manner that the planes of the flanges will be perpendicular to each other at all times during the bending operation; and still further to bend the angle-irons without warping the flanges by lateral distortion; the bending pressure being exerted uniformly on one only of the angle-iron flanges.

A further object of the invention is to provide a means whereby one-half of the two-part bending-rolls may be easily and readily adjusted longitudinally to receive between them flanges of angle-irons of various sizes or dimensions.

A still further object is to provide an adjusting means for vertically adjusting one of the bending-rolls to bend the angle-iron to the curve of the desired radius.

With the above and other objects in view, which will appear in the following specification, the invention consists in certain new and novel features of construction, arrangements and combination of parts and their equivalents, as will be more fully described hereinafter and finally pointed out in the claims hereto appended.

Referring to the accompanying drawings forming a part of this specification wherein like references denote similar parts throughout the several views: Figure 1 is a front elevation of my improved angle-iron bending machine, showing in dotted lines an angle-iron being bent. Fig. 2 is a side elevation thereof. Fig. 3 is a cross-sectional view taken on line 3-3 of Fig. 2. Fig. 4 is a sectional detail on line 4-4 of

Fig. 2 showing the gears for rotating the two lower rollers. Fig. 5 is a detail of a lower and an upper bending roll, the lower one being shown in cross-section.

The machine comprises mainly three driven two-part adjustable rolls A, B and C disposed on horizontal shafts 1, 2 and 3. Shaft 1 carrying roll A is journaled in bearings 4, which are vertically adjustable in the frame-members 5. The three rolls between which the angle-irons are engaged are arranged in close triangular relation, two of the rolls B and C, being the lower ones, are mounted on non-adjustable shafts journaled in the frame-members 5 and the third or upper roll A is arranged midway between the lower rolls, as clearly shown in Fig. 1 of the drawing. Shafts 2 and 3 are driven by means of the gear 6 mounted on shaft 7 and meshing with gears 8 and 9 respectively and best illustrated in Fig. 4. Shaft 7 is in turn driven by means of a train of gears 10, 11, 12, 13, 14 and 15 mounted on shafts 7, 16, 17 and 18 respectively. Shaft 18 is the power-driven shaft and is driven by any suitable means, such as belts running over loose pulleys 19 and 20 controlled by a suitable clutch 21, which is actuated by means of the lever 22 through the connections 23 and 24.

To permit the vertically adjustable roll A to be driven, I provide shaft 7 with a gear 25 and shaft 1 with a gear 26, which are adapted to mesh with an idler-gear 27 mounted on an auxiliary shaft 28 journaled in one end of the two pairs of toggle links 29 and 30. This link connection permits the idler-gear 27 to be retained in mesh with gears 25 and 26 as shaft 1 is raised or lowered. This arrangement also permits roll A to be adjusted while the machine is either in motion or stationary.

The means for vertically adjusting roll A comprises a screw 31 secured to each journal-bearing and entering a threaded bushing 32 mounted on frame-members 5. The upper end of each bushing is provided with a bevel-gear 33 meshing with the bevel-gears 34 mounted on the horizontally-disposed shaft 35. This shaft is rotated for raising or lowering the roll A by means of a suitable hand-wheel 36 or similar device. This arrangement permits each end of shaft 1 to be raised simultaneously.

37' is a bending-roll fixed to the shaft 1 and 37 designates a pair of bending rolls fixed to shafts 2 and 3 respectively. Each of the above rolls is preferably provided with a hard steel rim 38. The upper roll 37' mounted on shaft 1, it will be observed, is of less width of face than the two lower rolls 37, the object of which is to permit the heel of the angle-iron to be engaged by the rims of rolls 37 when the flange is being bent in, as indicated by dotted lines in Fig. 5, and to cause the periphery of roll A to engage the upper face of one of the angle-iron flanges when the flange is being bent outwardly.

The adjustable bending rolls designated A, B and C each comprise a cylindrical body having a neck 39, the periphery of each roll being preferably provided with a hard steel face 40. The adjustable rolls A, B and C are each slidably secured upon the shafts 1, 2 and 3 by means of a feather 41. Similar feathers 41 are secured to each of the shafts 1, 2 and 3 and are received in the slots or ways 42 of the rolls A, B and C. The end of each shaft 1, 2 and 3 is provided with a threaded stud 43 adapted to take a nut 44 carrying the spaced peripheral flanges 45 and 46. These flanges are adapted to engage either side of an apertured plate 47 sunk into the end face of the neck of each roll A, B and C. A lock nut 48 is also threaded on the stud. The lock-nut having been loosened, the nut 44 may be turned in either direction to move the rolls A, B and C longitudinally upon the shafts 1, 2 and 3, thereby widening or narrowing the flange space between the rolls 37', 37, 37 and the rolls A, B and C, according to the direction in which the nuts 44 are turned.

The means for preventing lateral distortion or warping of the angle-irons as they are being bent to the desired curvature comprises a roll 49 rotatably mounted between a pair of arms 50. These arms 50 are slidably mounted in a suitable bearing 51 forming a part of the front frame-member 5. The roll is adjustable longitudinally by means of the screw 52. This screw, as shown in Fig. 2, is connected at one end by means of a cross-head to the arms 50. The opposite end is threaded through an adjusting nut 49' received in a cut-away portion of the bearings 51. One of these angle-iron warping or lateral distortion-preventing rollers is arranged on each side of the machine, as clearly shown in Fig. 1.

The rolls 49 are each preferably arranged at an incline so that the axis of the roll lies at substantially right angles to the angle-iron being bent. This permits the outer face of one of the angle-iron flanges to bear against and rotate the rolls 49 as the angle-

iron is propelled to-and-fro by means of the bending rolls A, B, C, 37' and 37.

The operation of my invention is as follows: First, the flange-space between the bending-rolls is adjusted to receive one of the flanges of the angle-iron to be bent. The warping or lateral distortion rolls are next adjusted to engage one of the angle-iron flanges. The rolls are then rotated in one direction until the angle-iron has all but left one of the sets of lower bending-rolls; then the machine is preferably stopped; the upper bending-roll is then lowered to increase the curvature of the angle-iron during the backward travel of the bending rolls. This to-and-fro operation and the progressive lowering of the upper bending roll is repeated until the desired curvature of the angle-iron or T-iron is secured.

Having thus described my invention, what I claim and desire to secure by Letters Patent is:

1. In an angle-iron bending machine, the combination with a frame and a train of driving gears, of a non-adjustable driven shaft, a pair of non-adjustable bending-roll shafts arranged in a horizontal plane below said driven-shaft and parallel therewith, a vertically adjustable bending-roll shaft arranged above said non-adjustable driven-shaft, a pair of toggle links connecting said vertically adjustable shaft and said driven-shaft, gears on said shaft, an idler gear revolvably mounted at the intersection of said toggle links and engaging the gears of said shaft respectively, a set of two-part bending rolls mounted on each of the aforesaid bending-roll shafts, one part of each bending-roll being horizontally adjustable with relation to the other part, which part is fixed, whereby to increase or decrease the flange-space between each set of bending-rolls.

2. In an angle-iron bending machine, the combination with a plurality of shafts, a set of bending-rolls mounted on each shaft, each set comprising a roll fixed to each of said shafts, and a roll arranged on each shaft adjacent said fixed roll, said latter rolls being longitudinally adjustable upon their shafts to increase or decrease the flange-space between the two rolls of each set, and means operatively connecting said adjustable rolls and their shafts, said means adapted to force the rolls either toward or away from the corresponding fixed rolls to effect their relative adjustment.

In testimony whereof, I affix my signature in presence of two witnesses.

FRANK V. BURMAN.
